(57) **CLAIM**

The ornamental design for an eyeglass and eyeglass components, as shown and described.

DESCRIPTION

FIG. 1 is a front perspective view of the eyeglass and the eyeglass components of the present invention;
FIG. 2 is an alternate front perspective view of the eyeglass and eyeglass components of the present inventions;
FIG. 3 is a front elevational view thereof;
FIG. 4 is a rear elevational view thereof;
FIG. 5 is a left-side elevational view thereof, the right-side elevational view being a mirror image therof;
FIG. 6 is a top plan view thereof; and,
FIG. 7 is a bottom plan view thereof.
Phantom lining, where utilized, is for illustrative purposes only and is not intended to limit the claimed design to the features shown in phantom.
